[57] CLAIM

The ornamental design for a beverage can insulator, as shown and described.

DESCRIPTION

FIG. 1 is a top plan view of a beverage can insulator showing my new design;

FIG. 2 is an elevational view thereof, other elevational views being a mirror image thereof;

FIG. 3 is a bottom plan view thereof; and,

FIG. 4 is a longitudinal sectional view thereof, taken along line 4—4 in FIG. 1, to better show curvature of inside visible surfaces thereof.
